UNITED STATES PATENT OFFICE.

DAVID STODDART, OF SAN FRANCISCO, CALIFORNIA.

VALVE-GEAR FOR STEAM-ENGINES.

Specification of Letters Patent No. 26,301, dated November 29, 1859.

To all whom it may concern:

Be it known that I, DAVID STODDART, of the city and county of San Francisco and State of California, have invented a new and Improved Adjustable Cut-Off for Steam-Engines; and I do hereby declare that the following is a full and exact description of the same, reference being had to the accompanying drawings and to the letters of reference marked thereon.

The purpose of my invention is the usual office of a steam-engine cut-off, to open the steam valve at the commencement of a stroke, and afterward close it again at some required period of the stroke, and thus permit the steam to work expansively.

The accompanying drawings illustrate the invention as applied in the manner I believe to be the best.

20 Figure 1, shows its attachment to the puppet valves of a Mississippi steamboat engine.

A and B are two cams of a well known shape, commonly called "full stroke cams." B has only one-half as much throw as A.

25 C and D are the cam yokes.

E is a rocking bar, which is so connected to the yokes that it may vibrate as they move, and transmit its motion to the valve-rock-shaft through the cam rod F. E is 30 connected to D at the center, to C at one extremity, and to F at the other extremity.

The cam A is fixed permanently to the shaft, and its office is to open the valve. The cam B is free to be turned around on 35 the shaft, and fastened by the bolt G to the other cam at any required position; its office is to close the valve, and the period of closing or cutting off is governed by its position on the shaft. In the drawing it is 40 set to cut-off about half stroke.

The operation of the contrivance is thus, the shaft turns as the arrow shows, and A moves its yoke and opens one of the valves, and then following after it B moves 45 its yoke and shuts the valve, then both yokes continue stationary until A reaches the opposite side of its yoke and moves it in the other direction to open the other valve, which in like manner is closed by B, 50 and a period of rest for the yokes again occurs, until the engine reaches its original position, having performed one revolution. This alternation of motion and rest will be 55 clearly apprehended on discussing the construction of the full stroke cam, see Fig. 2, required, to draw a full stroke cam that

will fill a given yoke, and have a given throw. Draw the line $a b$ equal to the given diameter of the yoke, find the point c by making $a c$ equal to the given throw, then 60 bisect $b c$ at d :— $d a$, $d b$, and $a b$, are three radii to describe the curves of the cam. From the same center r describe two circles with the radii $d a$, $d b$, assume the point n in the larger circle as a center and with the radius $a b$, describe the curve $l m$ and with m as the center describe $n o$. The shaded portion ($l m n o$) is the required cam which will always fill the yoke. Suppose it to revolve as the arrow shows: So long as any 70 point of the curve between o and l touches the bar h of the cam a point of the opposite curve between m and n will touch the other bar h' ; and since these curves are described from the center r , no motion of the yoke will 75 take place until the point l reaches h and the line $r l$ is square with h . The yoke will then move until the line $r m$ becomes square with h , and then remain stationary 80 until the point l reaches h' , and commences the throw in the opposite direction.

Refer again to Fig. 1. It is necessary in my invention that the yoke of the cam B should be at rest at the instant when the cam A commences to open the valve, so as to maintain the same lead in all cases; therefore B should never be ahead of A, so as to begin its closing action, before A has begun to open the valve; nor should it be so far behind A, but that its cut-off action will be completed before A begins to open the opposite valve. When the lines $r l$ in both cams coincide the steam valve will not open at all, and when $r m$ in B coincide with $r n$ in A, the engine will work "full-stroke"; and again the cut-off will take place according to any relative position of the cams between these limits. With the full-stroke cam, the smaller the throw in proportion to the diameter, the smaller will be the angle $l r m$, and the quicker will be the action of the cam. I employ this principle to obtain the quickest possible closing action for the valve, in the arrangement which I describe as the best, compared with two other modes wherein there is simply a transposition of parts. Thus B might be fixed and used as the opening cam, and A be adjustable and the closing cam, preserving the connections to the rocking bar as they are. The effect would be to open the valve quicker than the first arrangement,

which is not required, and also to close it slower which is a disadvantage. B having the smaller throw should always be the cut-off cam. Again, A and B might be made with an equal throw and the rocking bar be connected to the yokes at its extremities and to the cam rod at its center. In this case the opening and closing motions would be alike, and both slower than the opening motion of the first arrangement, because the cams would require to have twice the throw of the pin in the rock-shaft-arm whereas in the first arrangement the throw of A is only one-half the throw of the said pin. The arrangement in Fig. 1 is then the best because, while it opens the valve quickly, it closes it with greater rapidity than either of the other modes. It is not necessary that B should have just one-half the throw of A, it might have somewhat more or less, and its yoke be connected to the rocking bar above or below the center, in proportion to the throw. Proper mechanism could be employed, whereby the cam B could be adjusted while the engine is in motion.

Figs. 3, 4, 5 and 6 represent different positions of a slide valve wherein the exhaust port remains open after the cut-off has taken place, 4 and 5 are the positions of extreme throw, and 3 and 6 the cut-off positions. This motion for such a valve is not new and it only remains for me to show how to

obtain such a motion from my device. The motion of an assumed point in the valve may be represented in direction and extent by the arrows in Fig. 7. The long black arrow shows the opening throw and the short red arrow the return or cut-off throw for one steam port, and the long red and short black arrows show like motions for the other steam port; the distance between the two dotted lines is the distance between the cut-off positions which we will call p , and let q be equal to the length of one of the long arrows. I recommend the same arrangement as in Fig. 1, with this difference that the cam B should have a less throw than one half that of A, to obtain the proper cut-off positions. Construct the cam A with its throw equal to q and then the throw B will be equal to $q/2-p/2$.

Claim.

I do not claim the use of two cams to work the steam valve, but I claim the use of the fixed cam A, in combination with the adjustable cam B, and the rocking bar E, which is connected to the cam rod, and also connected to and operated by the cam yokes substantially in the manner described.

DAVID STODDART.
